UNITED STATES PATENT OFFICE.

JACOB A. HYLE, OF ATLANTIC CITY, NEW JERSEY, AND CLARENCE R. KEATLEY, OF LOS ANGELES, CALIFORNIA, ASSIGNORS TO CONTINENTAL RAILWAY SUPPLY CORPORATION, A CORPORATION OF DELAWARE.

RAILWAY-RAIL ANCHOR.

Application filed November 14, 1927. Serial No. 233,074.

This invention relates to a novel and improved one-piece rail anchor or anticreeper especially designed to be secured to the base portion of railway track rails and in engagement with stationary parts of the railway bed for the purpose of preventing longitudinal displacement of the rails during the travel of the rolling stock thereover.

The prime object of the invention is to provide a novel, simple, durable, economical, practical and thoroughly efficient anchor from a single piece of high grade spring steel of suitable dimensions and possessing maximum strength, which may be easily and readily applied to the base of a track rail and securely retained in its proper operative position thereon, and which will always effectively clamp the track rail and co-operate with a stationary part of the road bed to prevent the track rail from creeping.

Another object of the invention is to so construct our improved device that it will always maintain an extremely tight and effective frictional engagement with the track rail under any and all conditions of service.

Further objects of the invention are to so construct this novel rail anchoring device that it will successfully resist creeping of the track rail; that it may be removed and re-applied any number of times and at the same time always retain its effective tension and gripping power; that it provides the desired bearing surface contact with the railway tie and extends downwardly to the middle portion of the tie and into the road ballast, and is so shaped where it enters the ballast that the vibration and wave motion of the track rail will push the ballast apart so that it will not be in constant contact with said ballast thereby avoiding interference with the railway electric signaling system now employed; that it possesses the desired and necessary resiliency in securing it to the track rail, and the greater the twisting strain to which the said anchor may be subjected the more intense gripping action is imparted thereto.

The foregoing and such other objects as may appear from the ensuing description are accomplished by the construction, arrange-

ment, location and combination of the parts hereinafter more fully described, illustrated in the accompanying drawings, and particularly pointed out in the claims appended hereto, it being understood that slight changes in the precise form, proportions and minor details of the construction may be resorted to without departing from the spirit or sacrificing any of the advantages of the said invention.

In the accompanying drawings forming a part of the specification it will be seen that:—

Figure 1 is a perspective of the improved device embodying our invention, showing it in contact with the base of a track rail and in contact with a cross-tie which forms a stationary part of the railway road bed.

Figure 2 is a side elevation showing the anchor secured in its proper position to the base of a track rail, said rail being shown partly in dotted lines, and

Figure 3 is a plan of the novel rail anchor showing it detached from the rail base.

In the embodiment of our invention as illustrated, the numeral 1 indicates a railway track rail and 2 an underlying cross-tie forming a stationary part of the road bed, and supporting the rail 1, the said rail having a tendency to creep, when subjected to the excessive strain caused by the travel of the rolling stock thereover.

Our novel and improved rail anchor is formed from any suitable or desired metal, but is preferably formed from a single piece or flat bar of high carbon spring steel of the desired or required dimensions, and may be of any desired thickness or width, and is provided with a jaw portion 3, that portion constituting the jaw which overlaps and clamps the inclined upper face of the rail base being slit centrally and rearwardly to the point 4, and spread apart in opposite directions forming a V-shaped opening therethrough, as is clearly shown in Figs. 1 and 3.

The body portion of the anchor is formed with a downwardly extended spring loop portion 5 adapted to rest and provide a bearing surface in contact with the railway cross-tie 2, down to a point about midway of the height of said tie terminating at the

point 6, for the purpose hereinafter referred to, while its upwardly and outwardly extended portion 7 terminates at its free end with a stepped clamping end member 8 adapted to firmly and tightly grip one edge of the rail base, as clearly shown in the drawings, said portion 7 from the point 9 to its outer stepped end portion 8 being drop forged or compressed to make it about one-fourth of an inch of less width than the jaw and body portion 8' thereof, the object being to cause all of the strain to which the anchor is subjected to be imparted to the jaw and body portion 8' thereof to the point 9, hence the snapping stepped end portion or member is normally out of contact with the cross-tie, the same formation being utilized when applied to either side of the track rail, in order to prevent contact with the tie or tie plate from the point 9 to its outer end, thus rendering the anchor applicable to either side of the track rail.

By referring to Fig. 3 of the drawings it will be seen that the outer end portion of the anchor is narrowed and is not normally in contact with the tie, hence it will be readily evident that in the event that the rail has a tendency to creep, said end portion being carried forward by the rail imparts a sidewise twisting movement to the anchor, thus causing one of the split portions of the jaw member to ride upwardly in contact with the inclined upper surface of the rail base, thereby materially adding to the intensity of its gripping power and insuring an evertight gripping action on the track rail base from either direction.

It will be perceived that this anchor is formed with a depending portion that extends to about the center or midway of the height of the tie, thereby preventing any tendency of the tie to rock sidewise when severe strain is imparted thereto, thus insuring greater stability and unity to the parts, and the spring loop portion 5 is so formed that its top narrowed portion slightly overlaps the widened body portion of the anchor in order to furnish the proper resiliency in securing the anchor to the rail base and intermediate the ends of the anchor it is depressed or weakened slightly at the points 10 in order to create a greater tendency for the necessary springing action to certain parts of the anchor.

It will be seen that the anchor is so formed that its outer free end portion normally extends in a horizontal plane above the lower level of the base portion 12 of the jaw 3, so that when the anchor is adjusted to the track rail there will be continuous pressure upwardly, by the said end portion against the lower face of the track rail. Hence, when a blow is struck against the outer face of the depending body portion, or when a suitable tool is applied in contact

with said body portion, the outer free end portion will be caused to immediately snap upwardly and tightly clamp the edge of the rail base, and is maintained in such position due to the high tension or pressure exerted by the overlapping spring loop portion and the particular construction of the anchor, and owing to the continuous upward pressure of its outer end there is no possibility of the anchor loosening or dropping off, from the excessive vibration occasioned by the passage of the rolling stock over the track rails, or the rubbing up and down action against the tie as the wheels pass over the track rails.

Owing to the precise construction of this particular type of anchor it will be readily evident that the maximum strength is obtained and that the greater the tendency of the track rail to creep, the more intense will be its gripping power, thereby insuring a practical and thoroughly effective anti-creeper.

It will be understood that our anchor may be formed from any suitable or desirable material, and of any desired thickness and dimensions, such as may be required for the purpose for which it is intended.

The outer free end stepped portion is so formed as to provide a plurality of steps to compensate for excessive wear, hence when said end portion becomes worn, and the anchor is re-applied one or the other steps will snap into contact with the edge of the rail base, thereby always maintaining a tight grip against the edge of the rail base.

Having thus described our invention what we claim and desire to secure by Letters Patent is:

1. A single piece rail anchor comprising a flattened bar provided with a longitudinally split jaw portion, a depending overlapping spring loop portion, a narrowed stepped free end portion, and a plurality of depressed portions intermediate its length.

2. A single piece rail anchor comprising a flattened bar of spring steel provided with a longitudinally split jaw portion, a widened depending body portion terminating at the middle portion of a cross-tie, an overlapping narrowed spring loop portion, a narrowed and stepped free end portion, and a series of depressed portions intermediate its length.

3. A single piece rail anchor comprising a bar of metal having a widened jaw portion and depending body portion, said jaw portion being split longitudinally with a V-shaped opening between its ends, an overlapping spring loop portion, a narrowed and stepped free end portion, and a series of depressions formed therein intermediate its length.

4. A single piece rail anchor comprising a bar of spring steel formed with a longitu-

dinally split jaw portion at one end, a widened depending body portion extending to the middle portion of a cross-tie, a narrowed overlapping spring loop portion, a narrowed and stepped outer free end portion, and a series of depressions formed therein intermediate its length.

5. A single piece rail anchor formed from a bar of metal having a longitudinally split jaw portion, a widened depending body portion, a narrowed spring loop portion, and a narrowed and stepped free end portion.

JACOB A. HYLE.

CLARENCE R. KEATLEY.
